UNITED STATES PATENT OFFICE

2,096,102

CIGARETTE CONTAINER

Edwin I. Gordon, Chicago, Ill.

Application August 15, 1936, Serial No. 96,266

2 Claims. (Cl. 229—51)

This invention relates to a cigarette container, and more particularly to a container for cigarettes, small cigars and the like, equipped with means for readily opening a portion of one end of the package. An object of the invention is to provide a package suitable for cigarettes and the like with means for conveniently and readily removing a section of one end of the package. Other specific objects and advantages will appear 10 as the specification proceeds.

The invention is illustrated, in preferred embodiments, by the accompanying drawing, in which—

Fig. 1 is a perspective view of a package embodying my invention; Fig. 2, a broken view similar to Fig. 1 but showing the revenue stamp removed; Fig. 3, a view similar to Fig. 1 showing the package after a section of the top has been removed; Fig. 4, a plan view of the paper flat before it is folded to form the package in Figs. 1 to 3 inclusive; Fig. 5, a broken perspective view of a package showing a modified form of my invention; Fig. 6, a view similar to Fig. 5 but showing a section of the top freed but not completely severed; and Fig. 7, a plan view of a paper flat before it is folded to form the package illustrated in Figs. 5 and 6.

I am aware of the fact that perforations have been formed in packages for forming openings therein to permit the discharge of the contents therefrom. No one, however, to my knowledge, has ever been able to apply to a package like that commonly employed for cigarettes, in which the end portions are folded over each other, means for readily forming an opening therein near one end, the opening being so formed that the side walls of the package around the opening are free from any obstruction adjacent the opening, save as to the portion of the package which remains 35 still covered. With this construction, I find that the cigarettes can be readily retained in the package, even though a number of cigarettes have been removed, while cigarettes can be removed with the minimum of effort when desired. 40 A complete severance and removal of a section about one end of the package can be accomplished in a moment, in the operation of my invention, notwithstanding the fact that the paper flaps enclosing the end are folded into overlapping position, as shown more clearly in Figs. 1 and 2.

In the form of the invention illustrated in Figs. 1, 2, 3 and 4, I stitch a portion of the paper and foil enclosing the cigarettes with a lock stitch, or 50 other suitable stitch, which will tear the paper

when the threads are pulled. The stitch is formed very easily on the flat paper and foil body 10, composed of a strip of paper and an aligned sheet of foil, as illustrated in Fig. 4. Preferably the two threads 11 are severed at a point so that 5 the free ends thereof extend below the revenue stamp 12 after the revenue stamp has been applied, as illustrated in Fig. 1.

When the threads 11 are drawn, they tear the stamp 12, as shown more clearly in Fig. 3, then 10 tear through the top flap 13 of the paper and foil body 10, and then back along the edges of the fold in the body 10 to the edge of the strip 10. As shown more clearly in Fig. 4, the removal of that portion enclosed within the stitching threads 11 15 brings about a removal of one end section of the package. That end is exposed and permits the removal of cigarettes therethrough.

In the illustration given in Figs. 5, 6 and 7, the stitching threads 11a do not pass through the 20 overlapping folds 13, but only around the edges of one end of the package. However, in this operation, they do destroy a portion of the stamp 12a, as illustrated in Fig. 6. In the use of the form of the invention shown in Figs. 5, 6 and 7, a pull 25 of the threads 11a frees one end of the top. The top may then be bent back over the other side to permit the removal of cigarettes; or, if desired, the freed flap 14 may be torn away, thus reaching substantially the same result as was reached initially in the construction shown in Figs. 1, 2, 30 and 4.

It will be understood that other modifications may be made in the method of tearing one end of the package to expose the cigarettes or other 35 contents.

The problem of opening a package having one end closed by folded-over portions without, at the same time, completely opening the end of the package, is thus seen to be solved by a very simple 40 and inexpensive means, while at the same time providing a package which serves effectively to retain cigarettes therein while permitting the cigarettes to be removed readily when the package is tipped to one side to cause the cigarettes to 45 fall toward the side which is open. In the latter position, there is no obstruction to prevent end-wise movement of the cigarettes because the severance is at the free edge of the package. It will be understood that instead of stitching threads, 50 other suitable means for weakening the package sections may be employed for carrying out the spirit of the invention.

While I have described the invention in connection with a cigarette package, it is obvious that 55

the invention may be employed with other packages of various types.

The foregoing detailed description has been given for clearness of understanding only, and no unnecessary limitations should be understood therefrom, but the appended claims should be construed as broadly as permissible, in view of the prior art.

I claim:

- 10 1. In combination with a wrapper folded to form a package, said wrapper having transverse folds by which are formed four sides making an enclosure of rectangular shape and having longitudinal folds near its upper and lower edges forming end enclosures, a draw thread stitched along a portion of one of the longitudinal folds at one end of the package and having a free end extend-

ing therefrom, whereby a pull on the thread will sever a portion of the enclosure at one end of the package.

2. In combination with a wrapper folded to form a package, said wrapper having transverse 5 folds by which are formed four sides making an enclosure of rectangular shape and having longitudinal folds near its upper and lower edges forming end enclosures, a draw thread stitched along a portion of the longitudinal fold at the upper end 10 of the package and also having a portion stitched at right angles to said longitudinal fold and extending across to the upper edge of the wrapper, whereby a pull on the thread will sever and remove a portion of the enclosure at said upper end 15 of the package.

EDWIN I. GORDON.
